(57) **CLAIM**

I claim the ornamental design for a non-circumferential bra,
as shown and described.

DESCRIPTION

FIG. 1 is a front perspective view of the claimed design in
a worn configuration on a silhouette mannequin.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is an inner side elevation view facing the left side as
taken along line 8-8 shown in FIG. 2.

FIG. 9 is an inner side elevation view facing the right side
as taken along line 9-9 shown in FIG. 2.

FIG. 10 is a front view of the claimed design in an unworn
configuration; and,

FIG. 11 is a rear view of the claimed design in the unworn
configuration.

The invention pertains to an ornamental design for a non-
circumferential bra. The non-circumferential bra is shown in
a worn configuration on a silhouette mannequin in FIGS.
1-9. The non-circumferential bra is shown in an unworn
configuration, removed from the silhouette mannequin, in
FIGS. 10 and 11. The solid lines represent the bounds of the
claimed design, whereas those features shown in broken
lines, including the silhouette mannequin shown in FIGS.
1-9 and the lines 8-8 and 9-9 of FIG. 2, form no part of the
claimed design.
